Application June 23, 1947, Serial No. 756,501

8 Claims. (Cl. 30—15)

1

This invention relates to the class of cutlery and is directed particularly to improvements in can openers of the rotary drive wheel type.

An object of the present invention is to provide in a rotary drive wheel type of can opener wherein an oscillatable cutter carrier is employed, a novel resilient can rest mounted upon such oscillatable carrier and cooperating with a fixed can rest to maintain the can in a desired position while the end of the can is being cut out.

Another object of the invention is to provide a can opener of the above described character wherein the said resilient can rest functions to improve the traction of the teeth of the can driving wheel with the under edge of the rim or flange of the can with which said teeth engage to feed the can through the device in relation to the cutter.

Still another object of the invention is to provide in association with a can opener of the rotary drive wheel type and employing an oscillatable cutter carrier, a novel spring means for a resilient can rest mounted upon the cutter carrier, which has little tendency to oscillate the cutter carrier out of its operating position after it has been moved thereto by mechanism provided for such purpose.

Still another object of the invention is to provide a can opener of the rotary drive wheel type, employing an oscillatable cutter carrier which is not only maintained in exceptionally good alignment but which lies near the lateral plane of an operating gear quadrant forming part of the can puncturing thrust mechanism, which assures maximum efficiency and minimum friction between operating parts for easiest puncturing of the end of the can by the cutter.

Another object of the invention is to provide a can opener of the rotary drive wheel type, employing a gear quadrant as a part of a thrust mechanism by means of which a cutter is caused to penetrate or puncture the can top and an oscillatable cutter carrier, in which the said gear quadrant is independently pivoted from the cutter carrier in such manner that either is entirely free to oscillate independently of the other within predetermined limitations and such free and independent oscillatory movement of either the gear quadrant or the oscillatable cutter carrier, one with respect to the other, within such predetermined limitations is assured throughout the life of the device.

A further and more specific object of the invention is to provide a can opener of the rotary drive wheel type which is compact, exceptionally

2

easy to operate, efficient and inexpensive to produce.

The invention will be best understood from a consideration of the following detailed description taken in connection with the accompanying drawings forming a part of the specification, with the understanding, however, that the invention is not to be understood as limited to the exact details of construction shown and described since obvious modifications will occur to a person skilled in the art.

In the drawings:

Figure 1 is a view in elevation of the right hand or outer side of a can opener constructed in accordance with one embodiment of the present invention, the parts being in the position which they occupy when the cutter is in lowered or working position.

Figure 2 is a view in elevation of the left or inner side of the cutter structure, the handle or hand grip portion being broken away.

Figure 3 is a view in top plan of the opener.

Figure 4 is a vertical section taken substantially on the line 4—4 of Figure 1.

Figure 5 is a vertical section taken substantially on the line 5—5 of Figure 1.

Figure 6 is a vertical section taken substantially on the line 6—6 of Figure 2.

Figure 7 is a view corresponding to Figure 2 but showing the oscillatable cutter carrier turned or oscillated to non-working position.

Figure 8 is a view in elevation of the left hand or inner side of a second embodiment of the invention, wherein is also shown a wall mounting arm in replacement of the handle or hand grip shown in Figure 1.

Figure 9 is a vertical transverse section taken substantially on the line 9—9 of Figure 8.

Figure 10 is a vertical transverse section taken substantially on the line 10—10 of Figure 8.

Referring now more particularly to the drawings, especially to Figures 1 to 7 inclusive, the numeral 10 generally designates the body of one embodiment of the present invention which is designed to be held in the hand for use. In this embodiment the numeral 11 designates the body plate and formed integrally with such plate is the elongated portion 12 which forms a handle or hand grip.

The plate 11 is of maximum dimensions vertically as shown and the lower or bottom edge has formed integrally therewith the laterally turned or right angularly directed can rest 13 which lies upon the left or inner side of the body plate.

In the lower part of the body plate 11 directly above the center of the can rest foot 13, the plate is provided with a circular opening 14 in which is mounted a journal 15. The periphery of this opening 14 constitutes a bearing for the journal 15, the journal being of a thickness slightly greater than the plate 11 as clearly shown in Figure 4.

Extending through the journal 15 is a shaft or stem 16 which forms an integral part of a thumb and finger operating crank 17. This crank or handle 17 is disposed upon the right hand or outer side of the plate 11 and the shaft 16 has mounted thereon, upon the outer side of the plate 11, the gear pinion 18 while upon the opposite or inner side of the plate there is mounted on the shaft 16 the peripherally toothed can rim engaging driving wheel 19. The pinion 18 is secured between the side of the adjacent journal 15 and an intermediate portion 17' of the handle and stem structure. The free end of the stem 16 is flattened or swaged as indicated at 16' against the adjacent wheel 19 thereby securing this element firmly against the journal 15 and at the same time securing the three elements 15, 18 and 19 firmly upon the stem.

The stem 16 is of polygonal cross section and the openings in the elements through which it passes are of corresponding configuration and accordingly it will be readily seen that upon rotation of the crank or handle 17 these parts will turn as a unit.

Directly above the bearing opening 14 there is formed through the body plate the circular opening 20. Through this opening 20 extends the smaller diameter portion *a* of a pivot pin 21. The reference character *b* designates a portion of this pin which is of slightly greater diameter and which is disposed upon the right hand or outer side of the plate 11 as shown in Figure 4.

Mounted for oscillation upon the portion *b* of the pin 21 is a quadrant plate 22; the arcuate edge 23 of which is directed rearwardly from the pin 21 and is located adjacent to the rearward edge of the body plate 11. This rearwardly and downwardly directed arcuate edge 23 of the quadrant plate carries the gear teeth 24 which are designed to mesh with the teeth of the pinion 18 for effecting the shifting of the hereinafter described cutter into and away from working position upon clockwise or counterclockwise turning respectively of the handle 17.

The quadrant plate 22 has formed therethrough the short arcuate slot 25 which slot coincides with a longer arcuate slot 26 which is formed in the body plate 11. These slots are of the same width and both are struck from the pivotal center for the pivot pin 21.

Encircling the smaller portion *a* of the pin 21 is the journal collar 27 which positions in a bearing opening 28 formed centrally in the oscillatable cutter carrying disk 29. This journal collar 27 has an integral encircling flange *c* upon its inner or left end which bears against the inner side of the disk 29 to maintain the latter in position with respect to the body plate 11.

As shown in Figure 4 a portion of the plate 29 is pressed out adjacent to its periphery to provide the oblique or angular section 30. This section 30 which is oblique to the plane of the disk 29 has secured therein the journal rivet 31 upon which is rotatably mounted the cutter disk 32. The cutter disk is thus maintained in a plane oblique to the plane of the body plate 11 and when it is in working relation with the can rim engaging

driving wheel 19 as shown in Figure 4 the lower part of the periphery of the cutter overlaps the toothed periphery of the driving wheel and is spaced slightly therefrom to provide clearance for the wall of the can, the rim or flange being interposed between the top of the toothed periphery of the wheel 19 and the overlying adjacent edge of the portion 30.

The rearward edge of the body plate 11 is formed to provide or has attached thereto the inwardly extending can rim engaging rest 33, the bottom face of which is substantially in the plane of the bottom edge of the section 30 so that when the opener is in position upon the edge of a can the top of such edge or rim will have sliding contact with the underside of the rest 33 as will be readily apparent.

Secured in the oscillatable cutter carrier 29 is the reduced end portion *d* of a coupling pin 34 which extends through the longer arcuate slot 26 of the body plate and into and through the shorter slot 25 of the gear quadrant 22. Thus it will be seen that the quadrant has scope for very slight oscillatory movement independently of the pin 34 and then connects with the pin and effects its movement in the slot 26 and consequent oscillation of the cutter carrier plate 29.

At the forward side of the oscillatable cutter carrier plate 29 from the cutter 32 there is fixed in the plate 29 below the horizontal plane of the center of the plate as considered when the plate is in position to dispose the journal pin 31 in a common vertical plane with the pin 21 and the stem 16, the rivet 35 which is of polygonal cross section so that it is held against rotation in the plate. This rivet secures to the inner or left hand side of the plate 29 the terminal portion 36 of a resilient can rest 37. As shown most clearly in Figure 6, this resilient can rest is in the form of a U-shaped member, one side or leg of which has the terminal 36 integral therewith while the other side or leg is directed below the plate 29 toward the body plate 11 and is free of connection with either of these parts. This resilient lower leg which is designated *d*, is free to flex upon the application of pressure which may be applied by the edge of a can rim engaging against the underside thereof during the operation of cutting out the head or top of the can.

As shown in Figure 7 when the thumb and finger crank or handle 17 is rotated counterclockwise the plate 29 will be oscillated to swing the cutter and the resilient can rest 37 upwardly and forwardly and thus the rim or flange of the can may be readily positioned upon the toothed top edge portion of the driving wheel 19.

Figures 8 to 10 inclusive illustrate a second embodiment of the invention designed for mounting upon a wall bracket and employing a slightly modified spring rest construction.

In this second embodiment the body is generally designated 38 and comprises the arm 39 which is shown broken away at its rear end but which is designed to be attached to a suitable wall plate mount or other supporting means. The forward portion of the arm merges with the body plate 40, which plate is of maximum dimensions vertically, like the plate 11, and at its bottom edge has the inwardly turned or directed can rest 41. This rest like the rest 13 is designed to engage against the side wall of the can while the top edge of the can flange bears against the fixed rest 42 which is integral with the bottom edge of the arm 39 adjacent to the rear portion

of the plate 40 and cooperates with the resilient flange rest, about to be described.

Above the body engaging rest 41 the plate 40 has a bearing opening 43 for the reception of the journal 44. This journal has fixed therein and extending therethrough the shaft 45 which is of polygonal cross section and which has fixed to its inner end the can rim engaging driving wheel 46 and supports at the opposite side of the journal 44 the gear pinion 47 which corresponds to the pinion 18. Outwardly of this pinion 47 the shaft 45 supports a spacer washer 48 and upon the outer end of this washer it has secured thereto an end of a crank 49, the lower end of which, not shown, is adapted to have a suitable hand grip, not shown, secured thereto.

Above the bearing opening 43, there is formed in the body plate 40 an opening 50 through which extends the smaller portion a' of a pivot pin 51, the outer end of which pivot pin is enlarged in diameter as indicated at b' . This larger diameter portion b' of the pin 51 carries a gear segment 52 which is of the same form as the segment 22 to cooperate in the same manner with the gear pinion 47.

As shown in Figure 9 the smaller diameter portion a' of the pin 51 is of materially greater length than the small diameter portion a of the pin 21 and this portion a' carries the relatively long journal collar 53 which has the two spaced encircling flanges c' . The end of the journal collar 53 nearest to the body plate 40 passes through the center of the oscillatable cutter carrying plate 54 and the flange c' nearest to the body plate 40 engages the inner or left hand side of the plate 54 and maintains it in proper position with respect to the body plate.

The lower edge portion of the cutter carrying plate 54 is outpressed as shown in Figure 9, providing the angled or oblique portion 55 in which is mounted the journal rivet 56 which carries the disk cutter 51. This cutter, of course, cooperates with the driving wheel 46 in the same manner as the cutter 32 cooperates with the driving wheel 19.

The oscillatable cutter carrier has a forwardly extending part 54' which terminates in the inwardly turned flange 58. This flange 58 functions as a stop to limit the clockwise and counterclockwise oscillation of the resilient or yieldable can rest which is generally designated 59.

The can rest 59 comprises a plate portion 60 which lies against the inner side of the portion 54' of the cutter carrier 54 and is pivotally connected therewith by the rivet 61. The forward end edge of this plate 60 is cut off at a slight oblique angle to its length, providing the lower point or tip 62 which engages the adjacent side of the flange 58 and limits the downward swinging movement of the plate 60 on the pivot 61. Rearwardly of the pivot pin 61 the bottom edge of the portion 54' of the oscillatable cutter carrier 54 is provided with a recess 63. This provides for slight movement upwardly beyond the bottom edge of the portion 54', of the inwardly extending horizontal portion 64 of the can rest 59.

The upwardly swinging movement of the can rest 59 is resisted by a spring arm 65, one end of which is engaged as at 66 in an aperture in the rear end portion of the can rest plate 60, while the other end is in the form of a portion of a loop 61 which is engaged between the encircling flanges c' of the bearing collar 53, against the

underside of such collar as is clearly illustrated in Figures 8 and 9.

The bottom part of the portion 64 of the resilient can rest 59 is normally disposed below the plane of the under face of the can rim engaging rest 42, as shown in Figure 8, so that it will be apparent that when a can is mounted in the opener device upon the top part of the periphery of the driving wheel 46 and the cutter 57 has been forced downwardly through the top of the can so that it will be in the position shown in Figure 8, upward thrust will be applied to the resilient rest 59 and the spring 65 will maintain the flange in firm driving contact with the toothed edge of the wheel 46.

While it is believed that the manner of using the present opener in both of its embodiments will be readily apparent a short description of the operation will be given in connection with the first mentioned embodiment, it being understood that such description of operation will apply also to the second embodiment except for the slight difference in the operation of the resilient can rest 59.

It is also to be understood that while the illustration of the second embodiment has not included the arcuate slots in the body plate 40 and gear segment 52 which cooperate with the pin 68 in the same way as the slots 25 and 26 cooperate with the pin 34, such structure is duplicated in the second embodiment.

In operation of the opener, considering the structure illustrated in Figures 1 to 7 inclusive, if the oscillatable cutter carrier 29 is not in its extreme counterclockwise position, as illustrated in Figure 7, so that further counterclockwise oscillation thereof is prevented by the rivet pin or stud 34 engaging the lower end of the slot 26 of the body plate 11, the operating handle 17 is rotated counterclockwise, as viewed in Figure 1, until the plate 29 is in the position shown in Figure 7.

The device is then placed on the can so that the disk cutter 32 is over the rim or flange of the can and the can rest 33 is above the rim or flange of the can. As the device is held substantially horizontal by the handle 12, with one hand, the operating handle 17 is rotated clockwise with the other hand until the end is cut out of the can, upon completion of which the operating handle 17 is rotated counterclockwise until further rotation is prevented by the rivet or pin 34 engaging in the lower end of the slot 26, as shown in Figure 7, thereby releasing the can from the device.

As the operating handle 17 is rotated clockwise, the oscillatable cutter carrier 29 is oscillated from the position illustrated in Figure 7 to approximately the position shown in Figure 2, the disk cutter 32 puncturing the end of the can as it swings downwardly and rearwardly, inasmuch as the teeth of the can driving wheel 19 engage with the under edge of the rim or flange of the can. During such action the teeth 24 of the gear quadrant 22 are meshed with the teeth of the pinion 18 and the lower end of the slot 25 of the gear quadrant seats against the pin or stud 34, thereby oscillating the cutter carrier 29 to approximately the position shown in Figure 2.

After the lower and forward tooth of the gear quadrant 22 runs out of mesh with the teeth of the pinion 18, rearward thrust of the end of the can against the disk cutter 32 causes the oscillatable cutter carrier 29 to oscillate slightly further until the pin or stud 34 seats in the upper

end of the slot 26 of the body plate, thereby preventing further oscillation of the cutter carrier. A slight backlash then exists between the lower end of the slot 25 of the gear quadrant 22 and the rivet pin or stud 34. Gravity of the gear quadrant 22 then causes the lower and forward tooth of the quadrant to ratchet on the teeth of the pinion 18 as the operating handle 17 is rotated further clockwise to cut the end out of the can.

It is believed that it will be readily apparent that reverse or counterclockwise rotation of the operating handle 17 will reverse the stated operation of the parts to return the plate 29 to the position shown in Figure 7 for the release of the can from the device.

When a can is engaged in the device and the disk cutter is in the operating position shown in Figure 2, the rim or the flange of the can will force the lower portion or foot *d* of the can rest 37 upwardly, thereby placing the can rest, which is essentially a spring, under tension so that a downward pressure is exerted by the resilient can rest on the rim or flange of the can, which not only maintains the can in good alignment in the device as the end of the can is cut out, but also improves the traction of the teeth of the can driving wheel with the under edge of the rim or flange of the can. As shown, when in operating position, the can rest 37 is close to the disk cutter 32, but swings upwardly and forwardly as the cutter is moved from its operating position.

As previously stated the operation of the second embodiment is essentially the same as that of the first embodiment with the difference that the resilient can rest 59, instead of yielding as a result of resiliency in itself, yields against the resiliency of the spring arm 65 which normally urges it to swing downwardly to the position shown in Figure 8.

I claim:

1. In a can opener of the rotary drive wheel type including a body, a shaft passing through and rotatably supported by the body, means for turning the shaft and a can rim engaging driving wheel carried by the shaft to turn therewith; a pivot support on the body, a member mounted on said pivot support for turning movement, a cutter eccentrically carried by said member to be turned therewith in an arcuate path toward and away from an operative position with respect to the driving wheel, a pin carried by the member and extended perpendicularly therefrom for movement along an arcuate path concentric with the turning center of the member approximately 45°, means for establishing a driving coupling between said pin and the shaft for imparting turning movement to the cutter carrying member upon turning of the shaft in a clockwise or counterclockwise direction, a can rim engaging pressure applying element carried by the member to move therewith and adapted to engage and apply pressure to the top edge of a can rim when said member is turned to move the cutter into cooperative relation with the can rim engaging driving wheel, the said can rim engaging pressure applying means comprising an element designed to engage across the rim of the can, a pivotal connection between the element and the cutter carrying member for oscillation of the element on said member on an axis parallel with the turning axis of the cutter carrying member, and a spring connected between said element and the cutter carrying member and normally resisting

oscillation of the element upon movement of the element into contact with a can rim.

2. In a can opener of the rotary drive wheel type including a body, a shaft passing through and rotatably supported by the body, means for turning the shaft, a can rim engaging driving wheel carried by the shaft upon one side of the body to turn with the shaft and a gear pinion carried by the shaft to turn therewith upon the opposite side of the body from said wheel; a pivot journal carried by the body in spaced relation with the shaft and parallel thereto, a member supported upon said journal for turning movement, a cutter eccentrically carried by the member to move therewith into and out of operative relation with the driving wheel, said body having an arcuate slot therethrough concentric with the turning axis of the member, a pin carried by the member and extending through said arcuate slot, a gear quadrant mounted upon the body upon the opposite side thereof from the cutter carrying member and extending across said slot, said pinion being adapted to have toothed connection with the gear quadrant upon rotation of the shaft in one direction to move the cutter to a predetermined position away from the driving wheel and upon rotation of the shaft in the opposite direction turning the cutter into an operative relation with the driving wheel and then running free of the quadrant for continued rotation of the shaft and driving wheel, and a coupling between the quadrant and said pin.

3. A can opener of the character stated in claim 2, wherein the coupling between the quadrant and the pin comprises a short arcuate slot in the quadrant paralleling the first slot and through which the pin extends.

4. A can opener of the character stated in claim 2, with a yieldable can rim engaging pressure applying means carried by the cutter carrying member at the side of the cutter remote from the pin.

5. A can opener of the character stated in claim 2, with a fixed can rim engaging element carried by the body at one side of the driving wheel and cutter, and a yieldable can rim engaging pressure applying means carried by the cutter carrying member and positioned at the sides of the cutter and driving wheel remote from said fixed member.

6. A can opener of the character stated in claim 2, wherein said cutter carrying member is in the form of a disk, and a yieldable can rim engaging pressure applying means carried by and adjacent to the periphery of the disk upon the side of the cutter remote from said pin and adapted to move downwardly into contact with the top edge of a can rim when the disk is turned to move the cutter into cooperative relation with the driving wheel.

7. A can opener of the character stated in claim 2, wherein said cutter carrying member is in the form of a disk, and a yieldable can rim engaging pressure applying means carried by and adjacent to the periphery of the disk upon the side of the cutter remote from said pin and adapted to move downwardly into contact with the top edge of a can rim when the disk is turned to move the cutter into cooperative relation with the driving wheel, said pressure applying means comprising a substantially U-shaped element having spaced legs with one of said legs being secured to the disk to maintain the U-shaped member against movement independently of the disk, the other leg of the U-shaped member being di-

rected perpendicular to the plane of the disk and free for yielding movement.

8. A can opener of the character stated in claim 2, wherein said cutter carrying member is in the form of a disk, and a yieldable can rim engaging pressure applying means carried by and adjacent to the periphery of the disk upon the side of the cutter remote from said pin and adapted to move downwardly into contact with the top edge of a can rim when the disk is turned to move the cutter into cooperative relation with the driving wheel, said disk having an extended portion parallel with the body and said pressure applying means comprising a plate pivotally attached to said extended portion to oscillate on an axis parallel to the turning axis of the disk, an element integral with the plate for contacting the top edge of the can rim, and a spring connecting the plate with the disk supporting journal and functioning to resist movement of the plate in one direction under pressure applied thereto by the can rim.
